UNITED STATES PATENT OFFICE.

GEORGE P. BOURDELAT, OF ABERDEEN, NORTH CAROLINA.

HAIR-CUTTING MACHINE.

1,238,061.

Specification of Letters Patent. Patented Aug. 21, 1917.

Application filed August 30, 1916. Serial No. 117,620.

To all whom it may concern:

Be it known that I, GEORGE P. BOURDELAT, a citizen of the United States, and a resident of Aberdeen, in the county of Moore 5 and State of North Carolina, have invented a certain new and useful Improvement in Hair-Cutting Machines, of which the following is a specification.

One of the principal objects of my invention is to provide an improved machine, 10 designed especially for cutting or trimming hair on the human head, in which means is provided for rapidly and evenly cutting the hair, in a manner most comfortable to 15 a person whose hair is being cut, and for conveying all of the cut hair together with whatever dandruff may be loosened to a suitable receptacle, so that none of the cut hair will fall from the head onto the clothing of the person.

Another object of the invention is to provide an improved hair cutting device, the use of which is attended by advantages of coolness and comfort to the person whose 25 hair is being cut and by advantages of sanitation not ordinarily acquired in machines of this character.

A still further object of my invention is to provide an improved hair cutting machine, 30 in which a rotary cutter is driven by an electrical motor and serves to cut the hair, means also being operable by the motor for drawing the cut hair away from the head and for directing it into a proper receptacle.

A still further object of my invention is to provide an improved hair cutting machine which will be extremely simple, durable, efficient in operation and inexpensive 40 to manufacture.

With these and other objects in view, which will become apparent as the description proceeds, the invention resides in the construction, combination and arrangement 45 of parts hereinafter more fully described and claimed, and illustrated in the accompanying drawings, in which like characters designate like or corresponding parts throughout the several views, and wherein:—

Figure 1 represents a view in section taken longitudinally through a hair cutting machine constructed in accordance with my invention;

Fig. 2 represents a plan view of the stationary cutting blade, looking toward the smooth outer face thereof;

Fig. 3 represents a view in section taken transversely on the plane indicated by the line 3—3 of Fig. 1 looking in the direction indicated by the arrows;

Fig. 4 is a fragmentary longitudinal sectional view showing the machine as being equipped with a modified form of stationary knife, in which comb teeth are utilized for determining the length of the uncut hair;

Fig. 5 represents a plan view of the modified form of the stationary cutting blade, having the comb teeth;

Fig. 6 represents a fragmentary sectional view showing the device as equipped with a gage sleeve for gaging the length of the hair to be left uncut;

Fig. 7 represents an end view of the gage sleeve;

Fig. 8 represents a fragmentary view in section taken horizontally on the plane indicated by the line 8—8 of Fig. 1.

In carrying out my invention, I provide a cylindrical casing consisting of the segments 5 and 6 respectively, the segment 6 being provided with an internally threaded flange 7 into which the externally threaded inner end of the segment 5 screws, as indicated in Fig. 1, whereby the segments are detachably connected together.

Mounted within the segment 6 is an electrical motor 8 of suitable design, to which the cable 9 for supplying current is connected. This cable reaches the motor 90 through a suitably positioned opening 10 provided in the side wall of the cylinder. A perforated cover is threaded into place on the cylinder as shown, and it carries an adjusting screw 12 secured in place on the outer face of the cap 11 by means of a strap 13 riveted or otherwise connected at 14 to the cap. This screw 12 is internally threaded and screwed into engagement with it is a threaded stem 15 extending axially of the 100 motor 8. This sleeve 15 extends out through an opening in the cover 11, as shown. Thus, it will follow that when the screw 12 is turned in one direction or another the motor 8 will be shifted bodily longitudinally of the 105 segment 6 in one direction or another therein. In order that the motor 8 may be properly positioned in the segment 6 and held against rattling or accidental displacement, such segment is provided on its inner surface with a series of spaced ribs or ridges 16, against which the bands 17 of the motor

5 casing rest. The motor is free to slide longitudinally of the ribs under the influence of the screw 12, as the latter is manually turned whereby the motor may be adjusted, as before set out, and in order to prevent accidental rotation of the motor casing, the bands 17 may at one or more points where they intersect the ribs 16 be notched or recessed whereby to engage upon the ribs in 10 such a manner as to prevent the motor casing slipping or rotating around inside the segment 6.

15 A shaft 18 driven directly by the motor 8 extends axially through the cylinder segment 5 and mounted on the shaft 18 is a fan 19. The latter includes a hub 20 which slidably engages upon the shaft 18 and which carries a set screw or other suitable device 21 whereby the fan may be adjusted 20 in desirable position longitudinally of the said shaft 18.

25 The outer end of the shaft 18 is journaled in a bearing 22 formed at the hub or center of a stationary cutting blade indicated generally at 23. This cutting blade is preferably formed integrally with an internally threaded ring 24 which ring screws into the internally threaded outer end of the cylinder segment 5. Adjustably mounted on the 30 shaft 18 inwardly of the stationary cutter blade 23 and held in adjusted position on the shaft by means of a set screw or other suitable device 25, is a rotary cutter, indicated generally at 26. This cutter includes 35 a plurality of radiating cutting knives 27 connected at their outer ends by rims 28. The stationary cutter 23 similarly includes a plurality of radiating cutter blades or knives 29. The blades or knives 27 and 29 40 are preferably made triangular in shape as indicated in Fig. 8. The cutting edges 30 of the blades 27 are adapted to pass across the cutting edges of the stationary blades 29 as indicated so that a clean sharp cut can be 45 made.

50 In order that correct adjustment between the rotary and stationary blades may be attained, the stationary blade may be manually rotated in one direction or another and hence will be either drawn toward the rotary blade or moved away therefrom until the proper adjustment is acquired. If desired, the stationary blade may be left undisturbed and adjustment between the rotary 55 and stationary blades be obtained by turning the screw 12 in one direction or another thus bodily shifting the motor together with its shaft 18 and rotary blade into the correct position.

60 The cylinder segment 6 is provided with a transversely extending partition or baffle 31 having a curved upper portion 32, whose function it is to direct the cut hair out through an outlet spout or nipple 33 into a 65 suitable tube 34, from whence it is directed

into a suitable receptacle, (not shown). The hair as it is cut, thus is drawn by the fan 19 into the cylinder and is forced by the blast of air out through the tube 34 into the receptacle, so that none of the cut hair will fall 70 on the head of the person. Furthermore, the operation of the fan in sucking the air through the cutting blades will serve to draw the hair into proper position to be cut by the blades and will also serve to keep the 75 head of the person cool so that the operation of cutting the hair will be attended with a maximum degree of comfort.

80 The modified form of stationary cutter, shown in Figs. 4 and 5, is similar to the stationary cutter already described in that it includes a ring, 24^a and radial blades 29^a. The method of operation of the cutting blades is the same as already set out. The modified form of stationary cutter is characterized by the fact that it carries on its outer surface a plurality of comb teeth, indicated at 35, which project outwardly from the end of the ring 24^a and from the outer faces of the blades 29^a. These comb teeth 90 are adapted to retain the cutter at a predetermined distance from the surface of the head, so that the length of the hair to be left uncut is thus regulated.

95 An adjustable gage for the device also designed so that the length of hair to be left uncut may be determined, is indicated in Figs. 6 and 7, and includes a sleeve 36 internally threaded whereby to turn upon the outer externally threaded end of the cylinder 100 segment 5. This gage sleeve 36 at its outer end carries the cross strips or bars 37 adapted to bear against the surface of the head so as to retain the cutter at a predetermined distance therefrom. The gage 105 sleeve by being turned in one direction or another will bring the cross bars or arms 37 closer to or farther from the cutter so that the length of the hair to be left uncut may thus be determined.

110 Although I have described the preferred embodiment of my invention, I may desire to make such changes in the construction, combination and arrangement of parts as do not depart from the spirit of the invention 115 or the scope of the appended claims.

I claim:

1. A hair cutting device, including a cylinder having a stationary cutter adjustably mounted near one end, a motor adjustably mounted in the cylinder, a cap on the opposite end of the cylinder, cooperating means between the cap and motor whereby the latter may be slidably adjusted within the cylinder, a shaft operable by the motor 120 and having a bearing in the stationary cutter, a rotary cutter carried by the shaft cooperating with the stationary cutter and adjustable relatively thereto as the said motor 125 is adjusted, an outlet spout formed on the 130

- cylinder, a tube connecting said spout with a receptacle, a baffle arranged in the cylinder for directing material through the outlet spout, and a fan mounted on the shaft for creating a current of air into the cylinder through the stationary cutter and out through the outlet spout.
2. A hair cutting device including a casing having a rotary cutter mounted therein and including a plurality of radial cutting blades, a ring adjustably mounted on the casing, a stationary cutter carried by the ring adjustable relatively to the rotary cutter upon adjustment of the ring and including radial blades coöperating with the blades of the rotary cutter, and means for driving the rotary cutter.
3. A hair cutting device, including a cylinder having a motor adjustably mounted therein, a cutter mounted in the cylinder including a blade movable bodily with the motor, a cap carried by the cylinder, a threaded stem carried by the motor extending through said cap, and an adjusting screw mounted on the cap exteriorly thereof and engaging the stem whereby the motor may be adjusted in the cylinder for adjusting the blade.
4. A hair cutting device, including a
- cylinder having a stationary cutter mounted thereon, means whereby said stationary cutter may be adjusted relatively to the cylinder, a motor mounted in the cylinder, a rotary cutter adapted to be driven by said motor and movable bodily with the motor, and means whereby the motor may be adjusted whereby to adjust the rotary cutter relatively to the stationary cutter.
5. The combination in a hair cutting device, of a cylinder having a rotary cutter mounted therein, a stationary cutter adjustably mounted on the cylinder and co-operating with the rotary cutter, and a cylindrical gage adjustably mounted on the cylinder and having means for engaging the surface of the head to determine the length of hair to be left uncut.
6. In a hair cutting device, a casing having a motor mounted adjustably therein, means operable from without the casing for adjusting the motor relatively to the casing, a cutter carried by the casing, and a rotary cutter mounted for movement with the motor coöperating with the first-said cutter, said rotary cutter being adjustable relatively to the first-said cutter through adjustment of the motor.

GEORGE P. BOURDELAT.
